UNITED STATES PATENT OFFICE

2,281,407

METHOD OF MAKING ENAMELED CONTAINERS

John A. Bohnsack, Youngstown, Ohio, assignor,
by mesne assignments, to Porcelain Steels, Inc.,
Cleveland, Ohio, a corporation of Ohio

Application April 25, 1939, Serial No. 269,946

2 Claims. (Cl. 29—148.2)

This invention relates to containers of the tank or range boiler type and particularly to range boilers coated with vitreous enamel inside, or inside and outside.

In my co-pending patent application, Serial Number 262,117, filed March 16, 1939, I have illustrated and described an enameled sheet metal tank of the range boiler type comprising a tubular body and heads welded to opposite ends of the body. The enameled tank or boiler of that application has head flanges overlapping the body wall and welded thereto by an electric roll-welding process.

In the enameled tank or range boiler of the instant application, the heads are welded to the body by an electric flash welding process.

The most economical method for the construction of tanks or range boilers is, as is well known, to fabricate the walls thereof from joined pieces of sheet metal. Tanks or range boilers have been proposed in which the pieces are joined by riveting, or by welding, and coated with vitreous or porcelain enamel of the fired fused type, but such enameled tanks, particularly of the range boiler type which, in use, contain hot water or other corrosive fluid and are subject to internal pressure and to differentials of temperature in different parts thereof, have not been successful because of the inevitable development of cracks in the enamel particularly at the junctures of the pieces. The primary purpose of enameling a tank or range boiler is to prevent corrosion and ultimate perforation of the wall by the corrosive action of water or other fluid contained therein. The enamel coat must therefore be solid and complete, because a single crack or pin hole imperfection in the enamel will expose the sheet metal wall to corrosion and develop a leak in the wall.

Upon the homogeneous, principal surfaces of the tank or range boiler wall, a solid complete coating of vitreous enamel can be formed without difficulty; but to construct the junctures of the pieces so that the enamel will form solidly and evenly thereon and adhere thereto and not crack in use, as referred to, presents a problem.

One cause of the cracking of the enamel at the joints in a tank or range boiler of the type comprising a body and heads on the ends of the body, is the fact that when the tank or range boiler is subjected to internal pressure in use the heads tend to bend or bulge outwardly at their intermediate portions which puts strains on their peripheral portions at which the joints are made. The pieces at the joints, therefore, tend to move

relatively with a hinging or spreading movement which, however slight, will crack the vitreous enamel covering the joint.

The junctures of the parts must therefore be of such character as to join the adjacent pieces integrally throughout the juncture to prevent such relative movement and enamel cracking. Rivets have failed in this respect. Welding has been proposed, but welding itself presents other difficulties.

If the welds at the joints are made by torch welding or arc welding processes, the metal at the juncture tends to be porous and contain impurities, which makes difficult the formation of a solid complete coat of enamel over the juncture.

In my aforesaid pending patent application, I have overcome these difficulties in a tank or range boiler of the type in which the heads have flanges overlapping the ends of the main body, by roll welding the flanges to the body by a weld which integrally joins the flange and body all the way to the extreme axial end of the overlap of the flange and body. The juncture is therefore integral and prevents relative movement of the parts, and may be readily covered by a solid enamel coat.

In the tank or range boiler of the instant application, the parts are joined by flash welding which effects a completely integral juncture not subject to relative movement of the joined parts. It has been discovered, after long experimentation, that a flash welded joint between sheet metal pieces, after the flash fin has been tooled off, provides a metal surface of such pure and solid metal that vitreous enamel will readily adhere thereto, and form a continuous solid coat thereover.

In making a tank or range boiler by the flash welding process, and particularly when it is of the conventional type comprising a tubular body and a head welded on each end of the body, the last or second welded head makes of the tank or boiler a closed container, except for the relatively small threaded openings to which conduit connections are to be made in use, and therefore the removal of the flash fin of the second welded head, to surface the juncture so that it will take enamel, presents an additional problem, which has been solved in the boiler of the present application as will hereinafter be set forth.

Another cause for the cracking of the enamel on a tank or range boiler is that the parts from which it is fabricated bend or yield under internal pressure. This occurs in a tank of the type having heads secured to the opposite ends of a

tubular body when the body is not perfectly circular in cross section and when the heads, particularly if they are not hemispherical, are not of sufficiently thick metal.

These problems and difficulties have been overcome in the boiler of the present application as will hereinafter be set forth.

It is among the objects of this invention:

To provide generally an improved container of the tank or range boiler type;

To provide an improved container of the tank or range boiler type having a solid and complete coat of vitreous enamel on the walls thereof;

To provide an improved container of the tank or range boiler type formed from a plurality of sheet metal pieces secured together by welded junctures of such character that vitreous enamel will form solidly and completely thereover and adhere thereto;

To provide a container of the tank or range boiler type formed of a plurality of sheet metal pieces flash welded together in an improved manner;

To provide an improved method of making a container of the tank or range boiler type;

To provide an improved method of making an enameled container of the tank or range boiler type from pieces of sheet metal welded together;

To provide an improved spud or threaded conduit connection for containers of the tank or range boiler type.

Other objects will be apparent to those skilled in the art to which my invention appertains.

My invention is fully disclosed in the following description taken in connection with the accompanying drawings in which:

Fig. 1 is a view with parts broken away and with parts in section illustrating an enameled range boiler embodying my invention, the view showing the boiler in the upright vertical position of use and with fragments of conduits communicating therewith interiorly;

Fig. 2 is a sectional view to enlarged scale of a spud conduit connection for a lower head of the boiler of Fig. 1 and illustrated in elevation in that figure and which may be utilized for connecting the other conduits to the boiler;

Fig. 3 is a view similar to Fig. 2 illustrating a spud conduit connection to the side of the boiler of Fig. 1 and which may be used for the other conduit connections to the boiler, Figs. 2 and 3 being modifications which may alternatively be used as desired;

Fig. 4 is a view illustrating a step of method of making the spud conduit connection of Fig. 3;

Fig. 5 is a view similar to Fig. 4 illustrating a modification;

Figs. 6 and 7 are respectively elevational and cross-sectional views of the tubular body of the boiler of Fig. 1 as it appears in the process of making the boiler;

Fig. 8 is a view partly in section and in some respects diagrammatic of an apparatus for performing a die drawing operation on the boiler body of Figs. 6 and 7;

Fig. 9 is a sectional view of one of the heads of the boiler of Fig. 1 illustrating a step which may be used in the method of making both the upper and lower boiler heads;

Figs. 10 and 11 are fragmentary views illustrating steps of method in the making of the boiler heads and operations performed upon the head of Fig. 9;

Fig. 12 is a view in some respects diagrammatic illustrating in simplified form an apparatus for

flash welding a head upon the body of the range boiler of Fig. 1 and indicating the welding of the other head on the body;

Figs. 13 and 14 are fragmentary views illustrating respectively a part of the head and body before and after welding;

Fig. 15 is a view in some respective diagrammatic illustrating in simplified form an apparatus for performing the method step of tooling off the flash fin on the inside of the boiler resulting from flash welding the first head;

Fig. 16 is a fragmentary sectional view taken from the plane 16—16 of Fig. 15;

Fig. 17 is a view having the above stated characteristics of Fig. 15 but illustrating the step of method of tooling off the interior flash fin resulting from flash welding the second head on the range boiler body, and also illustrating a method of removing both exterior flash weld fins;

Fig. 18 is a sectional view taken from the plane 18—18 of Fig. 17 with parts behind the plane of section omitted for simplicity;

Fig. 19 is a fragmentary view similar to a part of Fig. 17 illustrating a modification in the form of a tool of that figure.

Referring to Figs. 1 to 3 inclusive, which illustrate structural features of the enameled range boiler of my invention, I have shown in Fig. 1 the complete boiler. It comprises a tubular sheet metal main body or wall 1, preferably of circular cross-section, and having on its upper and lower ends respectively, heads 2 and 3 also of sheet metal, the heads having tubular flanges 4 and 5 welded to the opposite ends of the body 1 by an electric flash welding process to be described. As is well known, boilers of this class are subjected to internal pressure and therefore the heads 2 and 3, unless they are hemispherical in form, tend to bend or bulge outwardly, which will crack an enamel coat thereon, and to resist such bending the heads 2 and 3 are made from thicker sheet metal than the body 1, although the flange portions 4 and 5 thereof are of substantially the same thickness as the body 1 at the flash weld.

The flash welds are indicated diagrammatically by the dotted lines 6 and 7.

It will be understood that these flash welds join the metal of the flanges 4 and 5 with the body 1 so completely integrally that the juncture is not visible and that therefore the dotted lines 6 and 7 merely indicate the approximate locality of the welds.

The lower head 3 tapers downwardly all the way to an opening at its center, for a purpose to be described in connection with the process of applying and forming an enamel coat thereon, and the center of this head as shown in Fig. 2 and indicated in Fig. 1, terminates in an outwardly protruding hollow neck 8. A spud 9 is welded to the neck 8 and has exterior threads 10 thereon. A conduit connection nipple 11, to be referred to later, is mounted on the spud 9 by a coupling nut 12. By this construction, a pipe or conduit 13 threaded into the nipple 11 communicates with the interior of the boiler, through the lower head.

The conventional circulating system for range boilers, particularly when used as a supply of hot water for domestic purposes, calls for a pair of conduit communicating connections through the upper head of the boiler, and in some cases, a pair of lateral conduit connections through the side wall of the boiler, besides the single conduit

connection above described through the bottom head. In Fig. 1, I have shown at 14 and 15 necks press formed upwardly from the intermediate portion of the upper head 2, and spuds are welded thereto with which are associated conduit connection nipples 16 and 17 and coupling nuts 18 and 19 for effecting connection with pipes or conduits 20 and 21.

Similarly necks 22 and 23 are provided extending outwardly from the main body 1, and nipples 24 and 25 and associated coupling nuts 26 and 27 provide for connection with communicating pipes or conduits 28 and 29. The five conduit connections above referred to may all be alike and any suitable number or arrangement or location thereof may be provided.

As shown in Fig. 2, the spud 9 is provided with a tubular flange 30 thereon which is flash welded to the outer end of the neck 8.

If preferred, the modification shown in Figs. 3 and 4 may be used, Fig. 3 being referred to one of the side wall conduit connections. When this construction is employed for the spud connection, the side wall 1, or the head to which the spud is to be attached, is provided with a perforation 31, see Fig. 4, and the spud proper, 32, having the said external thread, in this case 33, is provided with a conical face 34, and with a cylindrical end portion 35, the latter substantially fitting the periphery of the perforation 31.

To weld this spud 32 in place, the cylindrical portion 35 is inserted in the perforation 31 with the conical shoulder 34 in engagement with the periphery of the perforation; and the wall and the spud are then forcibly pressed toward each other and electric current is passed through the spud and through the wall, welding the two together. This weld is of the general type of projection welding, the weld being indicated in Fig. 3 at 36. The parts may be pressed together between the welding electrodes themselves, indicated in broken line at 37 and 38.

In some cases, it may be desirable, as illustrated in Fig. 5 to bend the periphery of the perforation in the wall, outwardly into the form of a neck or bead 39, the outer edge of the bead engaging the conical shoulder 34, the weld in this case being performed in the same manner as that described for the parts illustrated in Fig. 4.

The welded-on spud arrangement of either Fig. 2 or of Fig. 3 may be employed in connection with the boiler of Fig. 1, on the heads or on the side wall thereof.

The lower head 3 has welded thereto a plurality, such as three, downwardly extending legs 40-40-40. These legs are preferably formed from sheet metal and may be of sufficient length to stand upon a floor or the like and constitute the support for the boiler. In practice, however, it is preferable to provide the usual or separate stand for the boiler, in which case the lower ends of the legs 40 rest upon the stand and center the boiler thereupon, thereby disposing the nipple 11 sufficiently far from the floor to permit convenient connection of the conduit 13 thereto.

In fabricating the boiler, the main body, heads, legs and spuds are all welded together and then the boiler is coated with porcelain or vitreous enamel over the entire inside or inside and outside surfaces. The inside coat of enamel is illustrated at 41 and the outside coat at 42. The outside coat may, if desired, also cover the legs 40. As shown in Fig. 2, (or in the alternative form of Fig. 3 if that be employed), the outside coat 42 extends all the way to the threads 10 (or to 75 enamel, is a welded juncture. I have found by

the threads 33) of the spuds. Furthermore, as one of the particular features of my invention, the inside coat 41, as shown in Fig. 2 (or in the alternative spud construction of Fig. 3), extends outwardly through the spud in an unbroken coat and over the outer flat face of the spud, as at 43.

The central opening through the spud terminates outwardly as at 44, Fig. 2 (and 45, Fig. 3) in a tapering or conical surface and the enamel coat forms thereover also as at 46.

Before securing the nipple on the spud, a packing gasket 47 is placed upon the outer enameled face 43 of the spud, and the nipple is drawn down thereupon in sealing relation thereto pressing the gasket sealingly upon the enamel at 43 by the coupling nut, the nipple preferably being provided with a conical bead 48 which forces the packing washer 44 down into the conical termination of the opening and upon the enamel at 46, as plainly shown in Figs. 2 and 3.

By this means the inside surface of the boiler, including the opening through the spud, is in every case coated and sealed against corrosion by the enamel coat all the way out to the end of the conduit threaded into the nipple, so that corrosion on every point of the inside boiler surface is prevented by the enamel coat. Obviously to prevent corrosion of the nipple and conduits themselves they may be made from corrosion resisting material. The packing gasket 48 may be of material soft enough to prevent injuring the enamel coat upon which it seals.

The nipple at the conduit 20, communicating 35 through the upper head 2, may be formed to permit the conduit to extend through the nipple downwardly into the boiler, as indicated in dotted line at 49, to a substantial distance below the upper head, and this may be the conduit outwardly 40 through which water is drawn from the boiler. By this means, as will be apparent, the upper end of the boiler will contain a quantity of air which may act as a shock absorbing cushion to absorb the shocks of hammering or the like in the conduit system connected with the boiler and thereby 45 prevent the inside enamel coat from being subjected to shocks to further insure that the inside enamel coat will not be cracked or otherwise injured thereby.

There are a number of features of the enameled range boiler thus far described which must be taken into consideration in the fabrication thereof and in the enameling thereof to insure that the enamel coat will form completely and solidly over the entire inner surface, or the inner and outer surface, and to insure that it will not crack when the boiler is subjected to internal pressure and to differentials of temperature in different parts thereof in use. As stated above, a single crack or 50 a single uncoated spot on the inside surface will be vulnerable to the corrosive action of hot water therein and will ultimately develop a leak. Nothing less than a completely perfect and durable enamel coat will suffice.

These features will be briefly discussed and this will be followed by a description of steps of the process of making the boiler by which these characteristics and features are embodied in the finished boiler.

As mentioned hereinbefore, the best known type of juncture between the several sheet metal pieces composing the boiler wall to join them sufficiently integrally to prevent relative movement therebetween and consequent cracking of the 70 75 enamel, is a welded juncture. I have found by

extensive experimentation that if the weld at such a juncture be so located that the enamel coat must form thereover on a substantial surface area thereof, the best type of welded juncture is a flash welded juncture. Any other type, such as 5 torch welding or electric arc welding, will leave the material at the juncture in such a condition physically and chemically, that it is difficult to form a solid enamel coat thereon.

In order to successfully flash weld the flanges 4 10 and 5 of the heads 2 and 3 to the ends of the body wall 1, these flanges and the body wall must be of substantially the same wall thickness and also of the same diameter.

It is desirable, for the reason stated above, that 15 the main portion of the heads be of thicker material than the flanges to prevent bending and enamel cracking, and therefore a reduction of thickness of the metal of the head must be effected at the zone of the weld. After the flash 20 welds have been made, the flash or fin which inevitably projects laterally from any flash weld, must be tooled off down to the solid metal, otherwise the enamel coat will not form completely 25 thereafter or adhere thereto.

When the spuds are welded on, if there are any 30 projections, irregularities or roughness at the welded junctures thereof, they may readily be removed by any suitable tooling operation, inasmuch as these junctures are accessible through the openings of the spuds themselves.

When the metal parts of the boiler have been 35 completely fabricated the wet enameling slip, which as is well known, may be a mixture of granular glass or frit and water and other ingredients, may then be applied to the walls of the boiler by immersing the boiler therein and rotating it if desired. The tank may then be withdrawn from the mixture and disposed in upright position and the surplus will drain off downwardly through the neck 8 in the lower head, and it is for this purpose 40 that this lower head tapers all the way outwardly through the neck in the form of a funnel. The coating of slip may then be dried in any suitable manner with or without heat, and the dried slip, if any, remaining on the external threads of the spud may be removed by running a nut or die 45 thereover, or by brushing them with a brush.

The firing of the dried enamel slip coat may be 50 performed in the usual manner.

Coming now to some of the more important 55 steps of the process of fabricating the metal parts of the boiler, I have shown in Figs. 6 and 7 the main body 1 as formed into hollow cylindrical form from sheet metal, the edges being welded together as at 50 by the electric flash welding operation. The flash fins, internal and external are 60 then removed. These operations are all well known and have been practiced in the flash welding of barrels and other containers having a longitudinal flash welded seam.

The thickness of the wall of the body is, of 65 course, determined by the thickness of the chosen metal from which it is made, but I have found that to predetermine its diameter to be the same as that of the flanges of the heads, above referred to, and to insure that it will be truly circular in cross section so as not to bend under internal pressure and crack the enamel coat, it is preferable to form it with a slightly excess diameter and then die draw it down to the requisite diameter and circular form. In Fig. 8 I have 70 illustrated, in some respects diagrammatically, an apparatus for performing this die drawing of the body.

A main frame 51 has a circular centering head 52 thereon having an upwardly extending annular circular flange 53 reduced in diameter to provide a shoulder 54. The flange 53 and shoulder 54 are proportioned so that an end of the body 1 may be telescoped over the flange and rest upon the shoulder in upright position.

Secured to the underside of the frame 51 is a pair of fluid pressure cylinders 55—55 preferably of the hydraulic type having pistons 56—56 reciprocable therein connected to piston rods 57—57 projecting upwardly through the frame 51, and having secured to their upper ends a drawing die 58 in the form of an annulus, the opening 59 in the annulus being accurately formed to a circle and to the desired diameter of the body.

A valve device 60 controls the admission of fluid pressure from a pressure source through a conduit 61 to the upper ends of the cylinders 55 by way of conduit 62—62 and the concurrent exhaust of fluid from the lower ends of the cylinders by conduits 63—63 and out to the source by a conduit 64. The said communication of pressure is effected at the valve 60 by moving a handle 65 thereof to the position shown. By moving the handle to another position pressure may be admitted to the lower ends of the cylinders and exhausted from the upper ends thereof, all in a well known manner.

At the start of the operation, the die 58 is moved to the upper broken line portion 58A by upward movement of the pistons 56—56 and the body 1 is placed on the centering head 52. The die 58 is then drawn downwardly and moved with a drawing operation over the outside of the body, an intermediate position therefor being shown in solid line, and at the lower end of its stroke, the die 58 moves beyond the lower end of the body 1 resting on the shoulder 52, to the lower broken line position 58B.

The body 1 may then be removed and the operation repeated for other bodies.

The seam weld 50 being a flash welded seam, there is no liability that this drawing operation will spread or open the seam.

The necks or perforations may now be formed in the wall and the spuds welded thereto, as described above.

In Figs. 9, 10 and 11, I have illustrated some of the steps of making the heads 2 and 3 of the boiler, Fig. 9 illustrating particularly the head 3, although the steps to be described may be employed also in the making of the head 2.

The head is press formed as stated from metal 65 thicker than that from which the body is formed, and as shown, the head is generally of cup form. When first formed, the head has a skirt 66 the outer end of which terminates in a laterally extending flange 67, and in the process of forming the head, the skirt in the outer portion thereof, as at 68, is drawn to a reduced thickness substantially that of the sheet metal from which the body 1 is formed and to the same diameter as the drawn diameter of the body. The skirt may, in a first press forming operation, be of the same thickness as the rest of the head and of the flange 67, and then the head may be gripped by the flange 67 to draw the skirt portion 66 to the desired thinner wall thickness, and to more exactly determine its diameter.

The head is then placed in a shearing die, comprising relatively reciprocable annular shearing elements 69 and 70, the element 69 having a shoulder 71 upon which the end of the skirt portion 68 may rest and having a cylindrical portion

72 fitting the inside of the skirt portion 68. The shear element 70 has an opening 73 therein fitting the outside of the skirt portion 68.

The two shear elements are reciprocated towards each other and the flange 67 is sheared off as shown in Fig. 11, leaving the skirt portion 68 as a tubular flange on the periphery of the head. The shearing operation leaves the skirt portion 68 with the desired thickness and diameter, and may in fact be relied upon to further true up the thickness and diameter. The force exerted on the skirt portion by this operation, forces the extreme end edge thereof, as at 74, against the shoulder 71 of the die element 69 thereby squaring off the end and removing the 15 roundness from this end which may have formed thereon, as at 75, Fig. 9, when the flange 67 was formed. As stated above, both heads 2 and 3 may be provided with reduced thickness skirt portions 68 by this process.

The heads are then flash welded to the opposite ends of the body 1. A part of this process is illustrated in Figs. 13 and 14. As shown in Fig. 13, the said reduced thickness skirt portion 68 is disposed in abutting relation with the end of the body 1; then electric current is passed through the points of engagement indicated by the line 76 and the flash welding arc forms therebetween. The metal melts or burns away from both pieces a considerable distance back from their original points of engagement, this distance in some cases being as much as one and one half times the thickness of the metal, the zone to which the metal is burned away being indicated in broken lines at 77 and 78. The two parts are then abruptly pressed together to effect the weld, the parts then taking up the positions shown in Fig. 14. The remaining portion of the reduced thickness skirt of the head may now be again referred to as the flange 4 for the head 2, or the flange 5 for the head 3. The resulting flash or fin at the weld is shown at 79 on the outside and at 80 on the inside.

Both of these flash fins 79 and 80 must be removed by tooling operations which will be described. The flash 80 on the inside being relatively inaccessible is caused to be of lesser extent than the flash 79 on the outside, by subjecting the interior of the body and head to air pressure while the flash welding is going on.

In Fig. 12 is illustrated, in some respects diagrammatically, an apparatus for performing this flash welding operation. The head 3 having the central spud opening, is welded on first and the head 2 last. At 81 is a cradle in which the body 1 is supported. The end of the body opposite to the head to be welded is closed and sealed air tight, by a cover 82 which rests in an annular notch 83 in a rear head 84 of the apparatus.

The head 3 is seated in a ring 85 on a head 86 reciprocable in ways 87-87. To hold the head 3 in the ring 85 any suitable means may be provided. That illustrated diagrammatically comprises a cap 88 threaded on the head spud and having connected thereto a threaded stem 89 which projects through a perforation in a bridging element 90 of the head 86 and has a nut 91 threaded thereon beyond the bridge. When the nut is turned, the stem 89 and cap 88 draw the head 3 securely into the ring 85 and seat it therein, thereby attaching the head 3 to the reciprocating head 86. The cap 88 seals the spud opening air tight.

The head 86 has a cam follower roller 92 thereon engageable with a rotary cam 93 on a shaft 94. 75

The roller 92 is normally seated in a notch 95 of the cam, that is to say, when the head 86 is in its fully retracted position illustrated.

One of the lateral spud connections to the boiler is closed and sealed by a cap 96 threaded on the spud and the other spud connection has a flexible hose 97 sealedly connected thereto.

The hose 97 is connected to a reservoir 98 of compressed air through an automatic valve device 99 and air under pressure is applied to the reservoir 98 by a compressor 100. The automatic valve device 99 is provided to maintain, within the boiler being welded, air pressure at a constant value. Some of the air passing into the boiler through the device 99 and the conduit 97 will leak out and a considerable portion thereof will flow outwardly radially through the gap and arc at the zone of welding, and in variable amount as the welding process proceeds. A valve device 99 is chosen which will maintain the internal pressure substantially constant in spite of this variation of leakage. Such devices are well known and any suitable or well known device may be employed.

20 Welding current is conducted to the head 3 and the body 1 in any suitable manner. The means shown comprises a transformer secondary 101, the opposite terminals of which are connected respectively to the head 3 and body 1 adjacent the edge 102 of the body and the edge 103 of the head, the secondary being energized by a transformer primary 104. Preferably a plurality, such as three, transformer secondaries will be employed connected to the body and head at circumferentially spaced portions. Two other transformer secondaries are indicated in the drawing by the terminal wires 101A and 101B. The electrical connection between the transformer secondaries and the head 3 and body 1, may be made by pressure contact of electrodes therewith, not shown.

25 In operation, the transformers are energized and the shaft 94 of the cam 93 is turned clockwise as viewed in the drawing, and acting upon the cam follower 92 propels the head 86 toward the left, moving the edges 103 and 102 into engagement with each other. The electric arc forms therebetween, as described in connection with Figs. 13 and 14, melting away the metal at the edges; the cam 93 feeds the head 3 toward the body 1 to maintain the arc and at the end of the feeding operation a projection 105 on the cam abruptly pushes the head against the body with an upsetting action, and thereafter the current is discontinued by de-energization of the transformers. The upsetting action forms the fins at 79 and 80 referred to, and the effect of the air pressure within the boiler is to cause most of the fin to form on the outside, as shown in Fig. 14. I have found that a suitable air pressure for this purpose is approximately 15 lbs. per square inch. The air pressure may be maintained within the boiler concurrently with the heating of the metal, or may be introduced just prior to the upsetting operation.

30 By maintaining the air pressure constant as described, I have found that not only will a smaller fin form, but it will be more regular and more uniform in extent than otherwise, which facilitates its removal in the manner to be described.

If the pressure within the boiler tends to disengage its opposite end from the cap 82, any suitable means which will occur to those skilled in the art, may be provided to secure that end of

the body 1 to the cap 82 and the cap to the head 34, one such means being shown for the head 3 at the right hand end of the boiler.

The head 2 may be welded on by an operation like that described above, in which case the head 3, now welded on, will be seated in the head 34, as indicated at 3 in broken lines, and the spud outlet therefrom may be sealed air tight by a cap 105, and a device or devices corresponding to the cap 88, shank 89 and nut 91 and bridge 90 may be provided to hold the head 2, having two spuds thereon, securely on the head 36, or on a similar head.

After the head 3 has been welded on, as described above in connection with Fig. 12, and before the head 2 is welded on, the inside flash fin 80 is toolled off, for the purposes described, and this may be done as illustrated in some respects diagrammatically in Fig. 15.

The body 1, with the head 3 welded thereon, is mounted in a cradle 106 with the spuds 32 projecting downwardly. One of the spuds is disposed in a recess 107 in the cradle 106, whereby it may reciprocate freely therein for a purpose to be described, and the other spud 32 has projected thereinto, a pin 108 mounted on a carriage 109 reciprocable in ways 110 on the cradle by a screw 111, which may be rotated in any suitable manner, for example by a handle 112.

The cradle 106 is supported adjacent to the head stock 113 of a lathe or like machine having a rotating spindle 114. In the preferred arrangement the spindle 114 or a chuck thereon, is provided with a taper socket 115. A tool shaft 116 is provided having at one end a taper shank 117 and at the other end having a co-axial stem 118. The shank 117 is inserted into the taper socket 115 with the tool shaft 116 disposed coaxially within the body 1, and with the stem 118 projecting outwardly through the central opening in the spud 9, which has previously been welded on the head 3.

The spud opening constitutes a bearing in which the stem 118 may rotate.

A fly cutter 119 is mounted on the tool shaft 116, projecting radially therefrom and having on its outer end a cutting point 120, which may be of the type employed for lathe work. The parts illustrating the cutter are shown fragmentarily in Fig. 16.

In operation, the shaft 116 is rotated by the spindle 114 of the said machine and the screw 111 is turned to feed the tool cutting point 120 longitudinally over, or back and forth over, the interior fin 80, thereby tooling it off and reducing the metal at the weld juncture to a smooth solid metal surface, such that vitreous enamel will flow evenly thereover and adhere thereto.

It is to be observed that the pin 108 in the opening of the spud 32 performs the joint function of preventing the body 1 from being rotated by the cutting action of the tool, and of reciprocating the body on the cradle 106 to move the work under the tool. During longitudinal movement of the body, the spud 9 moves axially over the stem 118, the spud opening therefore performing the joint function of providing a rotational bearing for the outer end of the tool shaft 116 and a longitudinal sliding bearing therefor.

It is after this tooling operation of the flash fin of the head 3 has been performed that the other head 2 is welded on by the process described in connection with Fig. 12.

When this second head has been welded on,

the body and two heads make a closed container except for the relatively small openings through the spuds in the heads.

The body 1 and the two heads 2 and 3 welded thereto are now in the condition illustrated in Fig. 17, in which the interior fin at the head 2 is indicated at 80A, the fin at the head 3 having been removed. I have solved the very evident problem of removing this flash fin 80A, in spite of its inaccessibility, by the method and apparatus illustrated diagrammatically in Figs. 17 and 18.

The boiler is mounted on a pair of roller supports 121-121 under the left hand end of the boiler as shown in Figs. 17 and 18, and upon a similar pair of roller supports 122-122 under the right hand end of the boiler. One of the rollers 121 is connected by a gear 123 and a pinion 124 to a driving pulley 125 by which the roller may be rotated to rotate the boiler upon its roller support, by power from any suitable source.

Upon the frame 126, upon which the roller supports are mounted, is provided a head 127 reciprocable in ways 128 by a rotary device 129 connected to the head 127 by a link 130. A tool 131 is provided in the form of a round rod of slightly less diameter than that of the spud opening in the spud 9 of the head 3. One end of the rod has a head 132 thereon pivotally connected at 133 to the reciprocatory head 127 for hinging movement in vertical planes. The opposite or working end of the tool is formed to have a cutting edge 134 thereon. In an intermediate portion of the rod 131 it is bent on a curve of relative large radius as at 135. The dimensional proportions of the rod 131 and the curvature at 135 are such that when the outer end portion of the rod is disposed substantially coaxial with the boiler the inner end will be in engagement with the inner wall surface of the boiler.

To dispose the cutting point 134 within the boiler the rod may be hinged upwardly around its hinging connection at 133 and the opening of the spud 9 may be telescoped over the cutting point of the tool and the boiler then placed upon the roller supports. The large radius of the curvature at 135 will permit the rod to be projected through the spud opening and at the same time substantially fit the same. When the head 127 is reciprocated, the cutting point 134 will be reciprocated over the fin 80A and tool the same off down to a solid metal surface over which vitreous enamel will flow evenly and to which it will adhere. As this reciprocatory cutting movement of the tool goes on, the boiler is concurrently rotated by any suitable means, for example that described above for rotating the supporting rollers, whereby the entire fin circumferentially around the boiler will be toolled off.

The tendency for the boiler to move longitudinally, toward the left as viewed in the drawing, when the longitudinal force of the cutting operation is communicated thereto, may be resisted and prevented by a roller 136 supported on the base 126 and engaging the head 2.

Various means may be provided to hold the cutting head of the tool against the boiler wall to cause it to tool off the fin and not ride thereover. One means would be to dispense with the supporting rollers 122 under the right hand end portion of the boiler. The weight of the right hand end portion of the boiler would then be impressed upon the right hand end of the tool rod 131 at the engagement of the spud 9 with

the rod, and this would cause the rod to hinge downwardly around its connection at 133 and force the point 134 of the tool downwardly. This downward force may be supplemented by a roller 137 rolling upon the upper side of the rod 129 and engaging it with downward force by the action of a spring 138, as an alternative means.

I have found, however, that in most cases, such applied force is unnecessary and in fact, the weight of the right hand end portion of the boiler itself is more than is necessary and therefore in the preferred arrangement some of this weight must be counter-balanced and to this end I provide the following arrangement.

The rollers 122 are rotatably mounted upon an arm 139 pivoted on the main frame at 140 and the free end of the arm 139 is supported upon a spring 141, the tension of which may be adjusted by a screw 142. By increasing the tension of the spring 141 any desired portion of the weight of the boiler may be carried by the rollers 122 and thereby the downward force on the rod at the spud may be adjustably varied to cause the tool point 134 to be suitably forced against the wall and to perform its cleaning and fin removing operation.

The outer fins 79 and 79A are readily accessible, being on the outside of the boiler, and may be removed at any suitable time during the fabricating process and by any suitable means.

In Fig. 17 one means is shown comprising a pair of grinding wheels 143 and 144 which may be driven by any suitable well known means and held against the fins 79 and 79A to grind them off and reduce the metal to a solid smooth surface over which enamel will completely form and to which it will adhere, while the boiler is being rotated during the removal of the interior fin 80A.

The cutting point 134 of the tool 131 may rest at its point upon the boiler wall as shown in Fig. 17, or it may be formed as in Fig. 19, having a portion 145 inwardly of the cutting point 134, which may rest upon the boiler wall during the reciprocatory movement.

While in the foregoing I have illustrated and described machinery in semi-diagrammatic form for performing various steps of the method of making the boiler embodying my invention, it is believed that those skilled in this art will understand how to supplement this diagrammatic disclosure with the necessary machine details of construction and without the necessity of further invention, if in fact, such additional details are necessary in constructing actual machinery.

An enameled range boiler embodying my invention, as described above and as illustrated in Fig. 1 has improved qualities which are not susceptible of illustration in a drawing, particularly in the esthetic quality of its appearance, its outside

surface throughout being in unbroken, jointless, smooth, lustrous surface of vitreous enamel of any desired color or mixed pattern of color known to the vitreous enameling art.

5 My invention is not limited to the exact details of construction nor to the exact elements of the method and of the machinery illustrated and described above. Changes and modifications may be made therein without departing from the spirit of my invention or sacrificing its advantages and which come within the scope of the appended claims.

I claim:

1. The method of fabricating a sheet metal range boiler which includes forming a sheet metal tubular boiler body and a pair of sheet metal heads having tubular edge portions, disposing the edge portion of one head in abutting relation with one end of the body and integrally welding it thereto by flash welding, tooling off the interior flash fin to a surface by a tool projected into the opposite open end of the body, providing a perforation in said head, disposing the edge portion of the other head in abutting relation with the other end of the body and integrally welding it thereto by flash welding, tooling off the interior flash fin of the last named welding operation to a surface by a tool projected through the said perforation, causing the said surfaces to be sufficiently smooth for vitreous enamel to flow completely thereover and adhere thereto, and coating the entire inside surface of the boiler including said tooled surfaces with vitreous enamel.

2. The method of fabricating a sheet metal range boiler which includes: forming a sheet metal tubular body and a pair sheet metal heads having tubular edge portions; disposing the edge portion of one head in abutting relation with one end of the body and integrally welding it thereto by flash welding; tooling off the interior flash fin to a surface by a tool projected into the opposite open end of the body; providing a central perforation in said head; disposing the edge portion of the other head in abutting relation with the other end of the body and integrally welding it thereto by flash welding; inserting through the said perforation an elongated tool having a cutting edge on its end portion; disposing the cutting edge adjacent the flash fin of the said other head; reciprocating the tool while concurrently rotating the body and heads to cause the tool cutting edge to remove the flash fin of the said head to a surface; causing the said surfaces to be sufficiently smooth for vitreous enamel to flow completely thereover and adhere thereto; and coating the entire inside surface of the boiler including said tooled surfaces with vitreous enamel.

JOHN A. BOHNSACK.
